DESIGN FOR A PISTOL

Stephen W. Dimick, West Hartford, Conn., assignor to Colt's Patent Fire Arms Manufacturing Company, Hartford, Conn., a corporation of Connecticut

Application April 21, 1939, Serial No. 84,480

Term of patent 14 years

To all whom it may concern:

Be it known that I, Stephen W. Dimick, a citizen of the United States, residing at West Hartford, in the county of Hartford and State of Connecticut, have invented a new, original, and ornamental Design for a Pistol, of which the following is a specification, reference being had to the accompanying drawing, forming part thereof.

Of the drawing:

Fig. 1 is a side elevational view of a pistol embodying the new design, the grip portion being shown in dot and dash lines.

Fig. 2 is a top plan view of the pistol shown in Fig. 1.

Figs. 3, 4, and 5 are sectional views taken on the lines 3—3, 4—4, and 5—5, respectively, in Fig. 1.

The dominant feature of the design is found in the flutes formed in the side surfaces of the barrel with the longitudinal center lines thereof below the longitudinal center line of the barrel as shown in Fig. 1.

I claim:

The ornamental design for a pistol, as shown and described.

STEPHEN W. DIMICK.
